UNITED STATES PATENT OFFICE.

URIAH O. LONG, OF LOS ANGELES, CALIFORNIA.

FIREPROOF CEILING-SLAB AND FLOOR-FORM.

1,179,851.

Specification of Letters Patent. Patented Apr. 18, 1916.

Application filed May 13, 1915. Serial No. 27,906.

To all whom it may concern:

Be it known that I, URIAH O. LONG, a citizen of the United States of America, residing at Los Angeles, in the county of Los Angeles and State of California, have invented certain new and useful Improvements in Fireproof Ceiling-Slabs and Floor-Forms, of which the following is a specification, reference being had therein to the accompanying drawing.

This invention relates to fireproof ceiling slabs and floor forms, and has for its object the production of a simple and efficient means for producing a fire-proof ceiling and floor form or constructing the same by means of a form or mold.

Another object of this invention is the production of a simple and efficient means for supporting the ceiling and floor slabs in firm engagement with the tile ceiling or joist and girders.

Other objects and advantages of the present invention will appear throughout the following specification and claims.

In the accompanying drawings:—Figure 1 is a longitudinal section through a portion of the ceiling and floor showing the tile blocks secured thereto. Fig. 2 is a longitudinal section through a portion of the ceiling and floor showing the scaffold work applied thereto. Fig. 3 is a longitudinal sectional view through a portion of the ceiling and floor showing a suspended ceiling support in connection with the tile and plastic concrete floor support. Fig. 4 is a longitudinal section through a portion of the ceiling and floor showing a modified form which may be employed having a thickened or depending girder. Fig. 5 is a detail perspective of the corrugated metallic form or brace used to form the arches of the ceiling. Fig. 6 is a detail perspective of the tile block used in connection with the present invention. Fig. 7 is a section taken on line 7—7, of Fig. 1. Fig. 8 is a detail perspective of an embodiment of the invention showing the corrugated metallic form having a closed end. Fig. 9 is a detail perspective of the V-shaped end of the tile block used in connection with the present invention for deep construction. Fig. 10 is a transverse sectional view through the corrugated reinforcing structure illustrated in the modified form shown in Fig. 8. This

Fig. 10 illustrates the method of connecting 55 the folded portions upon the corner of the metallic reinforcing member.

By referring to the drawings it will be seen that 1 designates the body of the ceiling and floor which is provided with a plurality of arches or archways 2 having a plurality of depending ribs 3 formed of plastic concrete material formed therein. A plurality of longitudinally extending braces 4 are placed within the depending ribs 3 as 60 clearly illustrated in Figs. 1, 2, 3 and 4. The archways 2 are braced by means of the corrugated sheet metal forms 5 as clearly illustrated in Fig. 1, the form being shown in detail in Figs. 5 and 8. This sheet metal 65 form is placed within the archway for the purpose of assisting in forming the plastic concrete floor and also in bracing the concrete floor without the necessity of employing metal laths and the like for reinforcing 70 the plastic concrete body.

By carefully considering Fig. 2 of the drawings it will be seen that the ceiling and floor are formed by placing the bottom mold blocks 7 upon the scaffold work 8 which 80 mold blocks 7 constitute a mold for the lower ends of the beams or ribs 3. The depending ends 9 of the sheet metal reinforcing mold 5 also fit upon the blocks 7 to constitute an efficient mold for the plastic concrete. This structure is illustrated clearly 85 in Fig. 2 of the drawings.

A central brace 10 may be employed for extending longitudinally of each archway 90 2 and may be formed of a substantially inverted V-shaped structure constituting a plurality of planks which have their adjoining edges connected by means of the wood screws 11. This brace 10 is supported upon a supporting plank 12 as illustrated clearly 95 in Fig. 2 of the drawings. The supporting plank 12 is of course supported upon the scaffold which is adapted to be placed in the desired position for supporting the mold formation 9, part of which comprises the 100 blocks 7 and the brace 10 as illustrated in Fig. 2 of the drawings.

As illustrated in Fig. 1 of the drawings it will be seen that the tile blocks 13 and 14 may be placed in their proper position 105 across the arches 2 and have their beveled ends 15 and 16 fitting in the notches 17 formed along the lower side edge of the

beams 3. This structure is clearly illustrated in Fig. 1 of the drawings.

By carefully considering Figs. 1 and 6 of the drawings it will be seen that the tile 13 is provided with an upwardly extending rib 18 which carries a wire 19 which has its upper end twisted together as illustrated by the numeral 20, the free ends 21 thereof being bent and firmly cemented 5 within the plastic concrete 1. The wire 19 passes through the upwardly extending rib 18 as clearly illustrated for the purpose of constituting an efficient support for the tile at the inner end thereof. The tile 13 is provided with a substantially V-shaped groove 22 along the side edge thereof for the purpose of receiving the tapering edge 23 of the tile 14 and constitutes an efficient interlocking means therefor. From the structure illustrated in Fig. 1 it will be seen that a very simple and efficient supporting means 10 has been produced for supporting the tiles 13 and 14 within the arches 2 of the ceiling.

Suitable ceiling decoration such as the 15 panels 24, 25 and 26 may be employed and secured to the lower ends of the beams 3 and tiles 13 and 14 such as illustrated in Fig. 1 of the drawings.

Attention is called to Fig. 6 of the drawings 20 which shows the method of manufacturing the tile, wherein the two sections of the tiles 13 and 14 may be formed in one piece, the portion or tile 14 being secured to the tile 13 at its lower edge 28 and at its 25 upper edge at the point indicated by the numeral 29, and extending at an angle of approximately 30° to the base of the tile 13. The tile 14 is secured to the upwardly extending portion or flange 18 of the tile 30 13 and is scored along the point indicated by the numerals 28 and 29 for facilitating the separation of the tiles 13 and 14.

Attention is further called to Fig. 5 of the drawings, which shows a detail perspective view of the sheet metal corrugated reinforcing plate which is adapted to fit in the arch. This plate is formed of sheet metal as above stated, and is so arranged as to have approximately five corrugations 45 or double crimps to an inch. Of course, this may be varied according to the desire of the manufacturer or builder.

As illustrated in Fig. 10 the corrugated form 5' may be provided with a closed end 50 also formed of corrugated material, and the closed end 30 may be fixedly secured along the corner thereof to the depending side portions 31 by means of lapping.

In Fig. 4 there is shown an embodiment 60 of the present invention, or in fact a further development of the device, wherein the plastic concrete 33 may be provided with the usual archways 34 having the corrugated metallic reinforcing plates 35 formed 65 in the archways, the archways being closed

at the lower ends by means of the tile blocks 36, which tile blocks have their projecting end portions 37 fitting in the notches 38 formed in the respective beams 39 of the ceiling. A depending girder or thickened 70 rib portion 40 is carried by the main girder running on the square angle with the girders 40 and 41, which are molded therein for the purpose of thoroughly reinforcing the girder or adding additional body thereto. Of course, the usual decorating panels 42 and 43 may be employed upon the ceiling when so desired.

Attention is now called to Fig. 3 showing a structure supporting a suspended ceiling 80 46 by wires 45 which are secured to the lower bracing beams 3. The lower ends of the suspending wires 45, are twisted in a spiral-like manner as indicated by the numeral 47 around the suspending wires for 85 constituting an efficient support for the suspended ceiling 46.

Attention is now called to Fig. 7, No. 52 which is a notch at the top of the upright edge of tile to permit wire to be flush of 90 tile.

Attention is now called to Fig. 8, No. 50 which is a small rivet through lap to hold corner in place on lap 51.

By carefully considering Fig. 7, it will 95 be seen that the construction of the wire loop 19 is shown disclosing the method in which the twisted ends of the wire loop are embedded in the cement. It should be understood that the rib 18 of the tile 13 is 100 not shown in Fig. 7, as it is thought unnecessary. It should be understood that Fig. 7 is a section taken at right angles to Fig. 1 on line 7—7.

By referring particularly to Fig. 8, it 105 will be seen that a modification of the corrugated form 5' is shown, wherein a substantially box-shaped structure having an open lower end is disclosed and the sides 30 of the corrugated form 5' have their ends 110 bent so as to overlap the side edges of the end pieces or side portions 31, the folded ends 51 being secured to the side portions 31 by means of the rivet 50.

In Fig. 9 there is disclosed a portion of 115 the tile 13, showing the manner in which the tile is molded prior to the application of the tile to a ceiling. It should be understood that by molding the portion 14 integral to the body of the tile, the same will 120 be convenient for shipment and the rib 18 will not be likely to become broken as would be the case if the portions 13 and 14 were shipped in separate pieces. By the structure shown in Fig. 9 and also in Fig. 6, it 125 will be seen that the portion 14 may be separated from the remaining portion of the tile 13 as above described. Fig. 9 merely illustrates the forward end of the tile showing the manner in which the forward end 130

of the tile—that is to say, the body portion 13—is connected to the separable portion 14 thereof.

Having thus described the invention what 5 is claimed as new, is:—

1. A device of the class described comprising a plastic concrete body, said plastic concrete body comprising a plurality of archways being separated by means of a 10 plurality of depending rib portions, bracing joists embedded within said rib portions, tiles spanning said archways, a corrugated reinforcing plate fitting upon the under face of said archways and the inner faces of said 15 ribs, panels secured to the under face of said tiles and the under face of said ribs, said tiles comprising a primary and an auxiliary section, said primary section provided with an upwardly extending flange portion, 20 said primary section also provided with a V-shaped groove along one side thereof, said auxiliary tile provided with a V-shaped edge fitting in said V-shaped groove of said primary portion whereby said tiles will be held in an assembled position, and suspending 25 wires secured to the upper edge of said flange of said primary portion and embedded within said plastic concrete body for efficiently supporting said tile within 30 said arch.
2. A device of the class described comprising a plastic concrete body, said plastic concrete body comprising a plurality of archways being separated by means of a 35 plurality of depending rib portions, bracing joists embedded within said rib portions, tiles spanning said archways, a corrugated reinforcing plate fitting upon the under face of said archways and the inner faces 40 of said ribs, panels secured to the under face of said tiles and the under face of said ribs, said tiles comprising a primary and

an auxiliary section, said primary section provided with an upwardly extending flange portion, said primary section also 45 provided with a V-shaped groove along one side thereof, said auxiliary tile provided with a V-shaped edge fitting in said V-shaped groove of said primary portion whereby said tiles will be held in an assembled position, suspending wires secured to the upper edge of said flange of said primary portion and embedded within said plastic concrete body for efficiently supporting 50 said tile within said arch, said tiles provided with projecting lips upon the sides thereof, said ribs provided with notches along the side edges thereof for receiving said lips and assisting in holding said tiles in engagement with said body. 55

3. A device of the class described comprising a plastic body, said body provided with a plurality of archways, separated by means of a plurality of depending rib portions, tiles spanning said archways, said 65 tiles comprising a primary and auxiliary section, said primary section provided with an upwardly extending flange portion, means formed upon the abutting edges of said tiles for permitting said tiles to interlock, means engaging said vertically extending flange portion and anchoring the same 70 in engagement with said plastic body, and means formed upon said depending rib portions for engaging said tiles and constituting supports for the outer edges of said tiles. 75

In testimony whereof I hereunto affix my signature.
